W. E. SCHWARZMANN,
DISTRIBUTING MECHANISM FOR MAGNETOS,
APPLICATION FILED SEPT. 27, 1918.

1,319,308.

Patented Oct. 21, 1919.

UNITED STATES PATENT OFFICE.

WOLFGANG ERNEST SCHWARZMANN, OF SPRINGFIELD, MASSACHUSETTS, ASSIGNOR,
BY MESNE ASSIGNMENTS, TO AMERICAN BOSCH MAGNETO CORPORATION, OF NEW
YORK, N. Y., A CORPORATION OF NEW YORK.

DISTRIBUTING MECHANISM FOR MAGNETOS.

1,319,308.

Specification of Letters Patent. Patented Oct. 21, 1919.

Application filed September 27, 1918. Serial No. 255,991.

To all whom it may concern:

Be it known that I, WOLFGANG E. SCHWARZMANN, a citizen of the United States, residing at 51 Bellclaire avenue, 5 Long Meadow, Springfield, in the county of Hampden, State of Massachusetts, have invented certain new and useful Improvements in Distributing Mechanism for Magnetos; and I do hereby declare the following to 10 be a full, clear, and exact description of the invention, such as will enable others skilled in the art to which it appertains to make and use the same.

The present invention relates to distributing mechanism for magnetos associated with internal combustion engines for ignition of the combustible mixtures therein, and more specifically relates to the electrical connecting means for the terminal or terminals 20 of the secondary winding of a high tension magneto of the sleeve type which has a stationary generating winding mounted on the armature and a magnetic sleeve rotatable in the air gap between the armature and field magnet.

In the sleeve type of magneto, it was customary heretofore to extend the connections for the terminals of the primary and secondary windings on the armature through 30 a hollow shaft of the sleeve. Those connections are closely adjacent each other, usually telescopically arranged, and thus require a comparatively thick separating layer of insulation which, upon failure in 35 service, short circuits all or a large part of the generating winding. Furthermore, the construction requires a larger size of hollow shaft and in other ways interferes with the most desirable form of parts of the magneto. 40 Moreover, this construction does not readily permit the use of an independent secondary winding with connections to its two insulated terminals for producing simultaneous sparks at two spark plugs in electrical 45 series.

In accordance with my invention, these difficulties are removed in arrangements for two spark ignition as well as single spark, the magneto producing four or any other 50 number of ignition currents in the stationary armature winding per rotation of the sleeve and the distributor, where use, being com-

bined with the magneto or separate therefrom, as desired. These results are attained in the preferred forms of construction disclosed hereinafter, by providing in association with the sleeve for rotation therewith, one or two brushes adapted to simultaneously engage the one or two stationary segments connected respectively to the one or two insulated terminals of the secondary winding. In the case of a magneto of this kind for single spark ignition, the single brush carried by the rotatable sleeve is electrically connected to a continuous collector 65 segment or ring, with which engages a stationary collector brush electrically connected to the rotatable brush of a single distributor, for a multi-cylinder engine; and in the case of two spark ignition, the two brushes carried by the rotatable sleeve to engage the two segments of the two insulated terminals of the secondary windings, are individually connected to two collector segments, and two stationary brushes, mounted for simultaneous engagement with the segments, are individually connected to two rotatable brushes of a twin distributor for the engine.

In this way, the connection from the mechanical interrupter to the insulated terminal of the primary winding extends through the hollow shaft of the sleeve at one end of the magneto, whereas the connection or connections to the secondary winding are brought out at the other end of the armature, thereby separating the high and low tension connections and readily adapting the construction to two spark ignition, as well as to single spark ignition.

In the accompanying drawings illustrating these preferred embodiments of the invention for one and two spark ignition systems, wherein, as an example, the magneto produces four ignition currents per rotation for an 8-cylinder 4-cycle engine, and the distributor is combined with the magneto, Figure 1 is a central vertical section of the magneto and distributor for single spark ignition; Fig. 2 is a section on line 2-2 of Fig. 1; Fig. 3 is a central vertical section of the apparatus for two spark ignition; Fig. 4 is a section on line 4-4 of Fig. 3; Fig. 5 is an end view of the stationary segments to which the two insulated terminals of

the secondary winding of Fig. 3 are respectively connected; and Fig. 6 is a section on line 6—6 of Fig. 3.

The magneto is of the well known sleeve type, having the bipolar field magnets 1, the stationary bipolar armature 2 with the primary winding 3 and secondary winding 4 mounted thereon, and the magnetic sleeve 5 rotatable in the air gap between the poles of the armature and field to produce four ignition currents per rotation in the secondary winding. The sleeve is mounted in the bearings 6, and the armature is carried in the bearings 7 supported by the sleeve, but is held against rotation therewith by a rigid fastening (not shown) between the hollow armature shaft 8 and a stationary part of the magneto located beyond the end of the hollow shaft 9 of the sleeve. The electrical connection between the insulated element of the mechanical interrupter (not shown) and the insulated terminal of the primary winding 3 is made by the insulated wire 10 extending through the stationary hollow shaft 8. The sleeve is driven from the engine at crank shaft speed by the gear 11 and in turn drives the distributor at cam shaft speed through the 1:2 speed reducing gearing comprising the pinion 12 fast with the sleeve and the gear 13 fast with the rotatable member of the distributor.

In the embodiment shown in Figs. 1 and 2 for single spark ignition, one terminal of the secondary winding 4 is connected to the terminal of the primary winding 3 and therethrough to ground in the well known way. The other terminal of the secondary winding is connected by the wire 14 to the continuous segment or slip ring 15 mounted in the insulating material 16 fast with the stationary armature 2. A single brush 17 is mounted in an insulating tube 18 fast with the rotatable sleeve 5, and continuously engages the segment 15. This brush 17 is electrically connected to the continuous collector segment or slip ring 19, by means of the wire 20, the grooved insulating material 21, carrying the collector segment, being integral with the insulating tube 18. A stationary collector brush 22 is carried by the brush holder 23 in engagement with the collector segment 19, and is electrically connected through the brush 24 and rod 25 to the distributor brush 26 fast with the distributor gear 13. The distributor brush is arranged to engage the spark-plug distributing contacts 27 in turn, each of those contacts being connected in a well known way to the individual spark plugs of the engine.

In this embodiment for single spark ignition, the ignition current produced in the secondary winding at each of the four ignition periods per rotation is conducted

from the insulated terminal of the secondary winding to a spark-plug distributing contact 27 by the electrical connection comprising the wire 14, segment 15, brush 17, wire 20, collector segment 19, brushes 22 and 24, rod 25 and distributor brush 26, thus producing a spark at the spark-plug connected to that contact. At the successive ignition periods, the ignition currents are conducted through the distributor contacts 27 in turn to the spark plugs of the other cylinders in their selected order of firing.

In the embodiment for two spark ignition shown in Figs. 3 to 6, the continuous segment 15 of the first embodiment is replaced by the two segments 28, insulated from each other and connected by the wires 29 to respective terminals of the independent secondary winding 4. Also the single brush 17 of the first embodiment is replaced by the two diametrically disposed brushes 30 arranged to simultaneously engage the segments 28 as they rotate with the sleeve 5. These brushes are connected by the wires 31 to the respective collector segments 32, which are diametrically disposed and insulated from each other in the insulating member 33. The single collector brush 22 of the first embodiment is replaced by the two diametrically disposed collector brushes 34, 35, which are mounted in the stationary brush holders 36 so as to simultaneously engage the rotating collector segments 32. The collector brush 34 is connected to the rotatable distributor brush 37 of the twin distributor by the conductor 38, contact 39, conductor 40, brush 41 and rod 42; whereas the other collector brush 35 is connected to the other distributor brush 43 by the conductor 44, contact 45, conductor 46 and outside wire 47. The two series of spark-plug distributing contacts 48 and 49 of the twin distributor are arranged to simultaneously engage the respective distributor brushes 37, 43, and are electrically connected by the wires 50, 51, to respective spark-plugs, of which two are usually provided in this arrangement for each cylinder.

At each of the four ignition periods per rotation of the sleeve 5 of this second embodiment, the ignition voltage generated in the secondary winding 4 is impressed across the adjacent spark-plug distributing contacts 48 and 49 of the two series, so that sparks are produced simultaneously at the two spark-plugs connected thereto by the wires 50 and 51. At successive ignition periods, sparks are produced simultaneously at the spark plugs of each other cylinders in their selected order of firing.

Having thus described my invention what I claim is:

1. In distributing mechanism for a magneto of the sleeve type having a stationary armature and a rotatable magnetic sleeve,

- primary and secondary windings mounted on the armature, an electrical connection extending from the primary winding to a point outside of the armature at one end thereof, a rotatable collector segment carried by the sleeve at the other end of the armature, an electrical connection between the secondary winding and the collector segment, and a collector brush mounted for engagement with the segment. 10
2. In distributing mechanism for a magneto of the sleeve type having a stationary armature and a rotatable magnetic sleeve, independent primary and secondary windings mounted on the armature, an electrical connection extending from the primary winding to a point outside of the armature at one end thereof, two collector segments carried by the sleeve at the other end of the armature, independent electrical connections extending between the two terminals of the secondary winding and the collector segments, and a pair of collector brushes mounted for engagement with the segments. 15
- 20
- 25
3. In distributing mechanism for a magneto of the sleeve type having a stationary armature and a rotatable magnetic sleeve, primary and secondary windings mounted on the armature, a hollow shaft supporting the sleeve at one end of the armature, an electrical connection extending from the primary winding through said shaft, a collector segment carried by the sleeve at the other end of the armature, and electrical connection between the secondary winding and the collector segment, and a collector brush mounted for engagement with the segment. 30
- 35
4. In distributing mechanism for a magneto of the sleeve type having a stationary armature and a rotatable magnetic sleeve, independent primary and secondary windings mounted on the armature, a hollow shaft supporting the sleeve at one end of the armature, an electrical connection extending from the primary winding through said shaft, two collector segments carried by the sleeve at the other end of the armature, independent electrical connections extending between the two terminals of the secondary winding and the collector segments, and a pair of collector brushes mounted for engagement with the segments. 40
- 45
- 50
- 55
- 60
- 65
- and the collector segment, a collector brush mounted for engagement with the segment, and an electrical connection extending from one end of the armature to the other to connect the collector brush and distributor. 70
6. In distributing mechanism for a magneto of the sleeve type having a stationary armature and a rotatable magnetic sleeve, independent primary and secondary windings mounted on the armature, an electrical connection extending from the primary winding to a point outside of the armature at one end thereof, a twin distributor arranged at that end of the armature and having a pair of distributor brushes driven by the sleeve, a pair of collector segments carried by the sleeve at the other end of the armature, independent electrical connections between the terminals of the secondary winding and the collector segments, a pair of collector brushes mounted for simultaneous engagement with the collector segments, and independent electrical connections extending from one end of the armature to the other to connect the collector brushes with the distributor brushes. 75
- 80
- 85
- 90
- 95
- 100
- 105
- 110
- 115
- 120
- 125
- 130
7. In distributing mechanism for a magneto of the sleeve type having a stationary armature and a rotatable magnetic sleeve; primary and secondary windings mounted on the armature; an electrical connection extending from the primary winding to a point outside of the armature at one end thereof; an electrical connection extending from the secondary winding at the other end of the armature and comprising a stationary segment connected to the secondary winding, a brush carried by the sleeve for engagement with said segment, and a collector segment electrically connected to said brush and carried by said sleeve; and a stationary collector brush mounted for engagement with the collector segment. 100
8. In distributing mechanism for a magneto of the sleeve type having a stationary armature and a rotatable magnetic sleeve; independent primary and secondary windings mounted on the armature; an electrical connection extending from the primary winding to a point outside of the armature at one end thereof; independent electrical connections extending from the secondary winding at the other end of the armature and comprising a pair of stationary segments connected to the respective terminals of the secondary winding, a pair of brushes carried by the sleeve for simultaneous engagement with said segments, and a pair of collector segments electrically connected to said brushes respectively and carried by said sleeve; and a stationary pair of collector brushes mounted for engagement with the collector segments. 115
9. In distributing mechanism for a magneto of the sleeve type having a stationary

armature and a rotatable magnetic sleeve; primary and secondary windings mounted on the armature; a hollow shaft supporting the sleeve at one end of the armature; a distributor driven by the sleeve and arranged at that end of the armature; an electrical connection extending from the primary winding through said shaft; an electrical connection extending from the secondary winding at the other end of the armature and comprising a stationary segment connected to the secondary winding, a brush carried by the sleeve for engagement with said segment, and a collector segment electrically connected to said brush and carried by said sleeve; a stationary collector brush mounted for engagement with the collector segment; and an electrical connection extending from one end of the armature to the other to connect the collector brush and the distributor.

10. In distributing mechanism for a magneto of the sleeve type having a stationary armature and a rotatable magnetic sleeve; independent primary and secondary wind-

ings mounted on the armature; a hollow shaft supporting the sleeve at one end of the armature; a twin distributor having a pair of distributor brushes driven by the sleeve and arranged at that end of the armature; an electrical connection extending from the primary winding through said shaft; independent electrical connections extending from the secondary winding at the other end of the armature and comprising a 30 pair of stationary segments connected to the respective terminals of the secondary winding, a pair of brushes carried by the sleeve for simultaneous engagement with said segments, and a pair of collector segments 35 electrically connected to said brushes respectively and carried by said sleeve; a stationary pair of collector brushes mounted for simultaneous engagement with the collector segments; and independent electrical 40 connections extending from one end of the armature to the other to connect the respective collector and distributor brushes.

In testimony whereof I affix my signature.
WOLFGANG ERNEST SCHWARZMANN.
